DEVICE FOR EFFECTING THE AUTOMATIC
MOVEMENT OF THE MATERIAL IN SEW-
ING MACHINES

Ramón Casas Robert, Barcelona, Spain

Application December 1, 1936, Serial No. 113,538
In Spain September 23, 1935

6 Claims. (Cl. 112—210)

This invention has among its objects to provide means for effecting entrainment or automatic advance of the material in sewing machines.

- 5 It is known that sewing machines are formed, in the platform or arm on which the sewing is done and in the zone of the reciprocating movement of the needle, with an aperture across which is projected a toothed member which follows a 10 rectilinear path, that is to say, a path comprising a horizontal portion, the teeth being then above the level of the platform, and then a substantially vertical downward portion, a further horizontal portion but in the reverse direction to the 15 first and below the platform, finally an upward substantially vertical portion. During this phase of the movement, the teeth of the member referred to grip the material which is being sewn and which is thus entrained during the first 20 horizontal movement, by reason of the pressure of the spring which acts on the presser foot of the machine and causes it to bear against the teeth. This operation is effected while the needle is in the raised position.
- 25 The means referred to are provided with devices for varying the advance of the material. In certain modern sewing machines, the direction of this movement can also be reversed according to the position occupied by the person operating 30 the machine.

The devices used, as well as the mechanisms which actuate them and the controlling and operating parts with which they are provided, are very complicated, are difficult to construct and to 35 assemble and are difficult and complex in working and are liable, on account of their complicated construction, to be easily damaged and to make a noise and to vibrate because they are made up of such large and heavy members.

40 The device according to the invention is distinguished by its compactness, which renders it effective for use in the most difficult cases and chiefly in machines in which the needle plate is mounted not on a platform but on an arm, which 45 facilitates various types of work, since it is possible, by reason of the small section of the arm, to introduce the arm into the garments which are being sewn even where they have a tubular form as in the case of sleeves and stockings.

50 The device according to the invention is also characterized by its extreme simplicity not only as regards construction but as regards control and operation since, by means of a simple control handle or grip, not only can the amplitude

of the movement of the toothed member be changed but also the direction of the movement. The essential feature of the device according to the invention is that the complete movement of the toothed member is effected by means of a single triangular eccentric so constructed that, in the course of two non-consecutive quarters of its revolution, it effects respectively the advance and the return of the toothed member and that, in the course of the two other quarters of its revolution which are alternate with reference to the quarters of the revolution first mentioned, it effects the necessary ascending and descending movements of the toothed member.

The device according to the invention is also characterized by the fact that the toothed member is displaced about a pivotal point so that its feed and return movements are effected while describing in each case an arc of a circle and its ascending and descending movements are effected along a radius of the said arc.

The device according to the invention is diagrammatically illustrated, by way of example, in the accompanying drawing—

Figure 1 is a longitudinal sectional elevation 25 of a sewing machine having a needle plate mounted on an arm and the device to which the invention relates.

Figure 2 is a transverse sectional elevation of 30 the arm.

Figure 3 is a diagrammatic view of the device with a graphical representation of its operation.

Figure 4 is a perspective view of a modified construction of the mechanism.

The device can be applied to sewing machines which have at their lower part, that is to say below their platform, a longitudinal shaft which is given a rotary movement. Rigid with this shaft, which is designated by the reference numeral 1 is a triangular eccentric 2 which actuates a connecting rod 3 provided with a square hole 4 in which the eccentric 2 fits exactly.

The other end of the connecting rod 3 forms a slide member positioned between the guides 6 which are carried by the head 7 of a connecting rod 6. The upper part of the crank 3 which forms the slide is circular; in the circular upper part is secured a spindle 5 normal to the plane of the connecting rod. On the spindle 5 is mounted a link 8 which is also mounted on another spindle 7 disposed parallel to the spindle 5.

The distance separating the geometric axes of the spindles 5 and 7 is the same as the distance separating the spindles 7 from a shaft 9 from 55

which the spindle 7 is carried by a member 8' lying parallel to the link 8 and secured at one end of this shaft 9 which extends the whole of the length of the platform of the machine and is mounted so that it can rotate through a determined angle. To the shaft 9 is firmly secured an arm 10 which projects above the platform as shown in Figures 1 and 2 but which may equally well project laterally. The arm 10 ends in 10 manually operable adjusting means formed as a screw 11 with a knurled head which screw can be made to move up or down as desired and can be held stationary at the desired height by means of a lock nut 11'. The point of the screw 11 bears, 15 when the arm 10 is displaced, against a flat, fixed plate 12 which constitutes the geometric chord of the arc described by the point of this screw 11 and which, furthermore, is greater the further the pointed end of the screw is from the shaft 9. 20 This allows the inclination which the arm 10 can assume to be varied and, thus also the inclination of the member 8' which displaces and carries the spindle 7, in order thus to vary the stitch and the direction of sewing. The mechanism described which serves to displace the spindle 7 around the shaft 9 as centre is secured in the sewing position desired by means of a spring formed in the present case as a rectangular steel plate 18, which is curved and provided 25 at the middle with a portion which bears against a depending member 18' formed on the arm 10 and which plate is secured on two opposite sides to the frame of the machine. The eccentric 2 further actuates a lever 13, provided with arms 30 13' after the manner of a yoke. The eccentric 2 fits exactly between the arms 13'. The lever 13 is mounted on a fixed pivot 14. At the end of the second arm of the lever 13 and by means of a gudgeon 15 is articulated the connecting rod 6 provided with a head 17 which carries the guides 6'. On the head 17 is secured the member 16 carrying the teeth. The form, the mounting and the configuration of this member, can be varied provided that its contour is formed as an 35 arc of a circle with centre on the axis of oscillation 15 of the connecting rod 6.

The device hereinbefore described can be constructed so as to be inoperative when desired, according to the nature of the work to be done by 40 the sewing machine, for example, for sewing a hem with the machine. In such a case, as illustrated in Figure 4, the triangular eccentric 2 is extended on the part opposite the shuttle by a tube or sleeve 2' in which is formed an annular channel in which are engaged the limbs of a manipulating fork member 2''. The actuating means may, however, be varied. At the opposite end to that which is provided with a tube or sleeve, the eccentric 2 is extended to form a truncated 45 portion which facilitates its entry both into the crank 3 with a square-hole 4 in its head, and between the limbs of the lever 13 which forms the lever articulated to the other connecting rod 6, so that thus when it is necessary to hold the 50 teeth of the machine stationary, it suffices to displace the triangular eccentric 2 so that it does not actuate the corresponding connecting rods 3 and 6.

The eccentric is secured to the shaft 4, to move 55 in the direction of rotation of the shaft, by means of a key which can be secured either to the eccentric itself or to the shaft, according to which arrangement is more mechanically convenient.

The device operates in the following manner:— 60 When the shaft 4 rotates, carrying with it the

triangular eccentric 2, the latter, during two non-consecutive quarters of the revolution actuates the forked lever 13, which causes an ascending and descending movement of the gudgeon 15, on which is mounted the connecting rod 6 carrying the head 17 and, with the latter, the toothed member 16. The said mechanism is conveniently guided at its upper part by the guides 6' carried by the head 17 and by the circular slider forming the upper part of the connecting rod 3. During 10 the other two quarters of the revolution made by the eccentric 2, which are also not consecutive and are consequently alternate with the first two, the eccentric 2 actuates the connecting rod 3 provided with the square hole 4 and imparts to it 15 an oscillatory up and down movement, and since the circular slider of the connecting rod 3 is pivoted by the spindle 5 to one end of the link 8 the said circular slider follows a curved path of oscillation with the spindle 7 as the axis of oscil- 20 lation.

The circular slider of the connecting rod 3 which slides between the guides 6' of the head 17 of the connecting rod 6 ensures the necessary freedom of movement to the two systems described of which it forms a part.

When the link 8, with the spindle 7 as axis, oscillates under the action of the spindle 5 which is mounted on the head or circular slider which moves between the guides 6' of the connecting rod 6, it cannot, owing to the sliding of this system of guides and slider, give to connecting rod 6 an up and down movement since the connecting rod is held at the axis 15. It can thus only move in the direction permitted by the constraint applied to it, that is to say, it can only describe an arc of a circle having as centre the point 15 and whose amplitude is proportional to the value of the horizontal component of the arc described by the spindle 5 whose geometric centre is at the 40 axis of the spindle 7. Further, the pivotal point 7 of the link 8 can be moved and held stationary by means of the pivotal adjustment of the shaft 9 which is manipulated by means of the handle 10—11 with reference to the path of the spindle 45 5. Therefore, according to the position occupied by the spindle 7, the horizontal component of the 50 arc described by the spindle 5 will be nil or will attain its maximum value in one or other direction according to the setting of the said handle. 55

In fact, when the spindle 7 is at the middle of the part of the path of the spindle 5 represented by the arc a of a circle (Figure 3), as is indicated at B, the horizontal component of the arc described, which in this case will be its minimum, is practically nil, so that the system 6—17—16 does not move horizontally. There is therefore no horizontal displacement of the teeth nor advance of the material but the group of members indicated effects its vertical up and down movement, since no adjustment is effected of the members of the mechanism producing this movement. When the spindle 7 changes position, following a regulating movement of the shaft 9 effected by means of the handle 11, and passes to a position either above or below its neutral point, wherever that position may be, the horizontal component of the path following the arc of a circle described by the spindle 5 is then followed and is greater according as the adjustment of the spindle 7 is greater. It will be readily understood that, according as the spindle 7 is above or below the neutral position, the level of which is indicated by the shaft 9, the movement nearly level with the platform of the member 75

which carries the teeth is effected in either a forward or rearward direction, as is shown in Figure 3. The shaft 1 upon which the eccentric 2 is mounted may either be a shaft provided specifically for the purpose or it may be the shaft which is normally employed to effect the movement of the shuttle of the machine.

The device described can vary as regards the size and shape of the different members forming it, and also as regards the materials used and as regards its construction and assembly in general, provided that the functional relations between the different parts remain the same.

I claim:

1. An automatic work-feed device for sewing machines, comprising a toothed feed head, a connecting rod at the one end of which the toothed feed head is mounted, laterally disposed guide surfaces provided on the said connecting rod adjacent to the toothed feed head, a second connecting rod the head of which fits slidably between the said guide surfaces, a rotatable driving shaft, a triangular eccentric mounted on the said shaft, a bell crank lever one arm of which is formed as a fork to engage the triangular eccentric and the second arm of which provides a pivotal axis for the first connecting rod, the disposition of the fulcrum of the bell crank lever and the triangular eccentric being such that during two non-consecutive quarters of a revolution of the eccentric the first connecting rod and with it the toothed feed head move up and down independently of the movement and of the position at any moment of the head of the second connecting rod which constrains the first connecting rod in respect of lateral movement, means for imparting to the second connecting rod from the driving shaft a reciprocating movement and means for determining the path of travel of the head of the second connecting rod in relation to the path of movement of the needle of the machine for the adjustment of the length of the stitch and the direction of the feed.

2. An automatic work-feed device according to claim 1, wherein the second connecting rod is formed with a square opening in which is fitted the triangular eccentric and which is provided with a spindle upon the head of the second connecting rod disposed between the said guide surfaces, a link pivoted to the said spindle, a second spindle of adjustable position parallel with the first spindle, upon which second spindle the link is also pivotally mounted, the said second connecting rod moving up and down during each of the two non-consecutive quarters of the revolution made by the eccentric, the said movement being alternate with the movements of the first connecting rod and the head of the second connecting rod being constrained by the said link to follow a path along an arc of a circle about the second spindle, the horizontal component of the movement along the said path causing the first connecting rod and the toothed feed head associated therewith also to follow a feed path which is an arc of a circle struck from the pivotal axis of the first connecting rod on the bell crank lever, the amplitude of the movement along the said feed path depending at any moment on the position occupied by the second spindle in relation to the horizontal plane which may be occupied by the two spindles.

3. An automatic work-feed device according to claim 1, wherein the second connecting rod is formed with a square opening in which is fitted the triangular eccentric and which is provided

with a spindle upon the end of the second connecting rod disposed between the said guide surfaces, a link pivoted on the said spindle, a second spindle of adjustable position parallel with the first spindle, upon which second spindle the link is also pivotally mounted, the said second connecting rod moving up and down during each of the two non-consecutive quarters of the revolution made by the eccentric, the said movement being alternate with the movements of the first connecting rod and the head of the second rod being constrained by the said link to follow a path along an arc of a circle about the second spindle, the horizontal component of the movement along the said path causing the first connecting rod and the toothed feed head associated therewith also to follow a feed path which is an arc of a circle struck from the pivotal axis of the first connecting rod on the bell crank lever, the amplitude of the movement along the said feed path depending at any moment on the position occupied by the second spindle in relation to the horizontal plane which may be occupied by the two spindles, and means for varying the position of the second spindle in relation to the said horizontal plane, comprising a shaft disposed in the said horizontal plane and in alignment with the centre of the circular path which the second spindle is constrained to follow, an arm upon the said shaft for the support of the second spindle, and a control handle secured to the said shaft for determining the position of the second spindle by rotary adjustment of the said shaft.

4. An automatic work-feed device according to claim 1, wherein the second connecting rod is formed with a square opening in which is fitted the triangular eccentric and which is provided with a spindle upon the end of the second connecting rod disposed between the said guide surfaces, a link pivoted to the said spindle, a second spindle of adjustable position parallel with the first spindle, upon which second spindle the link is also pivotally mounted, the said second connecting rod moving up and down during each of the two non-consecutive quarters of the revolution made by the eccentric, the said movement being alternate with the movements of the first connecting rod and the head of the second connecting rod being constrained by the said link to follow a path along an arc of a circle about the second spindle, the horizontal component of the movement along the said path causing the first connecting rod and the toothed feed head associated therewith also to follow a feed path which is an arc of a circle struck from the pivotal axis of the first connecting rod on the bell crank lever, the amplitude of the movement along the said feed path depending at any moment on the position occupied by the second spindle in relation to the horizontal plane which may be occupied by the two spindles, and means for varying the position of the second spindle in relation to the said horizontal plane, comprising a shaft disposed in the said horizontal plane and in alignment with the centre of the circular path which the second spindle is constrained to follow, an arm upon the said shaft for the support of the second spindle, a control handle secured to the said shaft for determining the position of the second spindle by rotary adjustment of the said shaft, a screw mounted upon the control handle for adjustment radially to the said shaft, means for locking the screw in any position of adjustment in relation to the operating handle, and a plane plate disposed to form a chord of the arc of movement of

the operating handle about the axis of the shaft, with which plate the point of the screw in the extreme positions of adjustment of the handle is caused to engage.

5. An automatic work-feed device according to claim 1, in which the shaft bearing the triangular eccentric is the shaft for effecting movement of the shuttle of the machine.

10. An automatic work-feed device provided with a toothed feed head, a connecting rod supporting the said toothed feed head, a rotatable driving shaft, a triangular eccentric mounted on the said shaft, a bell crank lever one arm of which is forked to engage the triangular eccentric, a fixed 15 fulcrum pivot for the said bell crank lever, a

pivot upon the second arm of the bell crank lever upon which the connecting rod is pivoted, spaced guide surfaces upon the said connecting rod adjacent to the toothed feed head, a second connecting rod having the one end disposed between the said guide surfaces and engaging the triangular eccentric by means of a square opening, the triangular eccentric being axially movable but non-rotatable on the shaft, one end of the said eccentric being truncated to facilitate engagement with the bell crank lever and the second connecting rod, a sleeve secured to the eccentric, an annular channel in the said sleeve, and an operating fork engaging the said channel.

RAMÓN CASAS ROBERT. 15
